UNITED STATES PATENT OFFICE.

LUCIUS A. WALTON, OF BYHALIA, MISSISSIPPI, ASSIGNOR TO HIMSELF AND DOUGLE McINTIRE, OF SAME PLACE.

IMPROVEMENT IN AUTOMATIC FANS.

Specification forming part of Letters Patent No. 118,832, dated September 12, 1871.

To all whom it may concern:

Be it known that I, LUCIUS A. WALTON, of Byhalia, in the county of Marshall and State of Mississippi, have invented certain new and useful Improvements in Machines for Keeping Off Flies from Tables, &c.; and I do hereby declare that the following is a full, clear, and exact description thereof, reference being had to the accompanying drawing and to the letters of reference marked thereon which form a part of this specification.

The nature of my invention consists in the construction and arrangement of a machine for keeping off flies, mosquitos, gnats, &c., from dining-tables, sick-beds, infants' cribs, lounges, or any place from which it is desired to keep them away.

In order to enable others skilled in the art to which my invention appertains to make and use the same, I will now proceed to describe its construction and operation, referring to the annexed drawing, which represents a longitudinal vertical section of my machine.

A represents the frame of my machine, in which is mounted a wheel, B, provided with buckets *a*, on the principle of an overshot water-wheel. C is a trough leading from a hopper, D, to a spout, E, immediately above the wheel. The machine may be run with balls, shot, sand, quicksilver, water, &c., as may be desired or convenient. The speed is controlled or regulated by a spring, *b*, inside

the trough C, which spring is operated by a thumb-screw, *d*, to open or close the space, thereby regulating the amount of shot, sand, &c., to pass through. The material used, after falling into the buckets *a a* and revolving the wheel, passes into a sack, G, suspended, as shown, in front of and under the wheel. Upon the wheel-shaft is a crank, *e*, connected by a pitman, H, with a crank-shaft, *f*, to which one or more fans are suitably attached.

This machine, or, rather, the frame-work thereof, may be constructed in any desired manner so as to stand upon a table or be attached to the ceiling or any other place where needed.

Having thus fully described my invention, what I claim as new, and desire to secure by Letters Patent, is—

The within-described machine, consisting of one or more fans, wheel B, trough C, hopper D, spout E, crank *e*, pitman H, and crank-shaft *f*, all arranged to operate substantially as and for the purpose set forth.

In testimony that I claim the foregoing as my own I affix my signature in presence of two witnesses.

L. A. WALTON.
